United States Patent Office

Des. 196,088
Patented Aug. 20, 1963

196,088

GROUND EFFECT VEHICLE

Paul C. Emmons, Buffalo, and Donald C. Wright, Tonawanda, N.Y., assignors to Bell Aerospace Corporation, Wheatfield, N.Y.

Filed Jan. 30, 1963, Ser. No. 73,378

Term of patent 14 years

(Cl. D71—1)

FIG. 3

FIG. 4

FIG. 1 is a top plan view of a ground effect vehicle, showing our new design;

FIG. 2 is a front elevational view thereof;

FIG. 3 is a side elevational view thereof; and

FIG. 4 is a rear elevational view thereof.

The side not shown is a mirror image of the side shown in FIG. 3.

We claim:
The ornamental design for a ground effect vehicle, as shown and described.
